UNITED STATES PATENT OFFICE.

JOHN J. SCHILLINGER, OF NEW YORK, N. Y.

FIRE-PROOF BUILDING.

SPECIFICATION forming part of Letters Patent No. 293,523, dated February 12, 1884.

Application filed October 10, 1883. (No model.)

To all whom it may concern:

Be it known that I, JOHN J. SCHILLINGER, a citizen of the United States, residing at New York, in the county and State of New York, have invented new and useful Improvements in Fire-Proof Buildings, of which the following is a specification.

This invention relates to improvements in fire-proof buildings, and has for its object to 10 provide novel and efficient means for covering and protecting the lower edges and the sides of the floor-beams and the under side of the flooring.

To this end the invention consists, essentially, 15 of a fire-proof sheathing molded in sections, and each section in a single piece, and of such shape that it extends across the lower edge of the beam and vertically along the sides thereof, and horizontally along the flooring.

20 The invention also consists in a fire-proof sheathing for the floor-beams and floors of buildings, molded in sections to the general shape of the lower exposed portions of such beams and floors, and with a depression in the 25 top of the floor-sections, to relieve the same from downward pressure.

The invention is fully illustrated in the accompanying drawings, in which Figure 1 is a cross-section of a portion of a floor with its 30 beams containing my invention. Fig. 2 is a plan view, omitting the floor. Fig. 3 is an inverted plan view.

Similar letters indicate corresponding parts.

The letter A designates the floor-beams, and 35 B the floor, laid on the beams in any usual or suitable manner.

C denotes the sections of the fire-proof sheathing. These sections are molded in any usual or suitable manner to the general shape 40 or outline of those portions of the beams and floor which are exposed in a lower direction—that is, each section is molded in one piece, of such shape that it will extend across the lower edge and vertically along each side of the 45 floor-beam, and then laterally or horizontally along the floor on opposite sides of the beam. It will be seen that by this construction the sheathing can be applied with the utmost facility, no changes of either the beams or the 50 floor being required, and hence a minimum cost is involved in the use of the article.

It is evident that the sections C of the sheathing can be divided from each other in various ways, and a detailed description thereof is 55 therefore deemed unnecessary.

The letter D indicates the depression in the top of the floor-sections of the sheathing. This depression extends nearly the whole width of the proper sections, and by its means the sections are relieved from downward pressure, 60 due to the sagging of the floor from natural causes, or by a heavy weight thereon. Another effect of the depression D is to cause the floor-sections to fit snugly, inasmuch as they come in contact with the floor only at the edges. 65

For the purpose of supporting the sections C in the required positions, they are attached to the beams or floor, or both, by nails, screws, or other similar fastenings, which may be located in the joints between the sections or in 70 the body thereof, and when the sections have been fastened the joints are preferably filled up by a suitable cement.

I am aware that it is not new to protect the lower exposed portions of floor-beams and 75 flooring by means of molded sections of fire-proof material, and such, therefore, I do not broadly claim; but

What I claim as new, and desire to secure by Letters Patent, is—

1. A fire-proof sheathing for the beams and floors of buildings, molded in sections, and each section in a single piece to extend across the lower edge and vertically along each side of the floor-beam, and laterally or horizontally along the floor, substantially as described. 85

2. A fire-proof sheathing for the floor-beams and the floors of buildings, molded in sections to the general shape of the lower exposed portions of such beams and floors, and with a depression in the top of the floor-sections, to relieve the same from downward pressure, substantially as described. 90

3. The combination, with the floor-beams and floor of a building, of a fire-proof sheathing molded in sections, each section being in a single piece and extending across the lower edge and vertically along the sides of the floor-beam, and laterally or horizontally along the floor, substantially as described. 95

In testimony whereof I have hereunto set my hand in the presence of two subscribing witnesses.

JOHN J. SCHILLINGER.
